UNITED STATES PATENT OFFICE.

WILLIAM THOMAS LANNING, OF DUNSMUIR, CALIFORNIA.

MOLD.

Application filed March 12, 1925. Serial No. 15,035.

To all whom it may concern:

Be it known that I, WILLIAM THOMAS LANNING, a citizen of the United States, residing at Dunsmuir, in the county of Siskiyou and State of California, have invented new and useful Improvements in Molds, of which the following is a specification.

This invention contemplates the provision of a mold designed for the construction of concrete walls of the like, the mold being susceptible of adjustment for walls of various thicknesses, and also adjustable to provide for a quick release from said walls as the occasion requires.

The nature and advantages of the invention will be better understood when the following detailed description is read in connection with the accompanying drawings, the invention residing in the construction, combination and arrangement of parts as claimed.

In the drawings forming part of this application, like numerals of reference indicate similar parts in the several views, and wherein:

Figure 1 is a side elevation of the mold structure.

Figure 2 is a top plan view.

Figure 3 is an end elevation.

Figure 4 is a sectional view taken on line 4-4 of Figure 3.

Figure 5 is a sectional view taken on line 5-5 of Figure 3.

Figure 6 is a sectional view taken on line 6-6 of Figure 1.

Figure 7 is a sectional view taken on line 7-7 of Figure 3.

Figure 8 is a sectional view taken on line 8-8 of Figure 4.

The mold forming the subject matter of the present invention includes a plurality of mold sections which are arranged in spaced parallel relation, there being four of said sections used in a double wall construction. Each section is preferably constructed of metal, and may vary in size and configuration without departing from the spirit of the invention. The sections are used in pairs, and the respective sections of each pair are indicated at 10 and 11. It will be noted upon inspection of Figures 2 and 3 that each section is also mounted on suitable supporting bars 12 which may be of any suitable design but preferably of U-shape

formation in cross section as shown in Fig-

ure 6. All of these bars depend from means designed to effect an adjustment between the sections of the respective pairs of sections, both for arranging the sections relatively for walls of different thicknesses, as well as to provide for a quick release of the mold structure from the walls when desired.

This adjusting means consists of an outer pipe 13 the ends of which are threaded to accommodate a cap 14 as shown in Figures 6 and 7, while slidably arranged within the pipe 13 is an inner pipe 15, the ends of which are also threaded to accommodate caps 16. Each of the caps 16 is provided with a threaded opening 17 which receive the threaded rod 18, the latter passing longitudinally through the inner pipe 15 and journaled in the caps 14 closing the ends of the outer pipe 13. The rod 18 projects an appreciable distance beyond one end of the pipe 13 and is equipped with a hand wheel 19, through the instrumentality of which the rod 18 is rotated in either direction to effect an adjustment of the mold sections toward or away from each other as the occasion may require. In other words when the rod 18 is rotated in one direction, the inner pipe 15 is moved in one direction longitudinally of the outer pipe 13 for the purpose of moving the corresponding mold sections 11 away from the corresponding mold sections 10, and when the rod 18 is rotated in the other direction, the inner pipe 15 is shifted to move the corresponding sections 11 of the mold toward the fixed section 10. It will be noted that the bars 12 which support the sections 10 terminate to provide sleeves 20 which surround the outer pipe 13 and are held fixed relatively to said pipe by fastening elements 21, while the corresponding upper extremities of the bars 12 which support the sections 11 are offset and fastened to the inner pipe 15 by bolts or the like 22. These offset extremities 23 pass through slots 24 formed in the outer pipe 13, so that they can be secured to the inner pipe 15 and moved therewith in the manner above described. Any number of these adjustable structures may be employed depending of course upon the length of the mold sections, two of said structures being illustrated in Figure 2. It is manifest that the sections 11 can be adjusted with relation to the sections 10 for walls of different thicknesses and moved in a direction away from the

sections 10 to allow the mold structure to be quickly separated from the walls when such separation is desired.

While it is believed that from the foregoing description, the nature and advantages of the invention will be readily apparent, I desire to have it understood that I do not limit myself to what is herein shown and described, and that such changes may be resorted to when desired as fall within the scope of what is claimed.

What I claim is:

1. A mold of the character described comprising a plurality of stationary and movable mold sections alternately disposed in parallel relation, spaced inner and outer pipes supporting the mold sections, means connecting the stationary mold sections with the outer pipe, means connecting the movable section with the inner pipe, and means for adjusting said inner pipe longitudinally

of the outer pipe whereby the movable sections can be adjusted toward and away from the stationary sections.

2. In a mold structure, inner and outer pipes, a threaded rod, passed through the inner pipe and associated therewith whereby said pipe can be moved longitudinally of the outer pipe, mold sections supported on the outer pipe and adjustable longitudinally thereon to vary the space between said sections, means for holding said sections fixed relatively to the outer pipe, said outer pipe having longitudinal slots, movable mold sections connected with the inner pipe through said slots and alternately disposed with respect to the first mentioned sections, and movable toward and away from the latter incident to the adjustment of said inner pipe.

In testimony whereof I affix my signature.

WILLIAM THOMAS LANNING.
